UNITED STATES PATENT OFFICE.

SAMUEL MARCUS, OF BROOKLYN, NEW YORK, ASSIGNOR TO F. & M. NOVELTY CO. INC., OF NEW YORK, N. Y., A CORPORATION OF NEW YORK.

DOLL'S HEAD AND EYES THEREFOR.

1,373,440.

Specification of Letters Patent.

Patented Apr. 5, 1921.

Application filed May 19, 1920. Serial No. 382,569.

To all whom it may concern:

Be it known that I, SAMUEL MARCUS, a citizen of the United States, and a resident of Brooklyn, in the county of Kings and 5 State of New York, have invented certain new and useful Improvements in Dolls' Heads and Eyes Therefor, of which the following is a specification.

The invention pertains to improvements 10 in the manufacture of heads and artificial eyes for dolls, and the invention consists in the novel features hereinafter described, and particularly pointed out in the claims.

One object of my invention is to provide 15 suitable means whereby glass eyes may be properly supported and allowed their rocking movement within the heads of dolls, and another object of the invention is to furnish suitable means whereby the eye-sets 20 may be conveniently secured by shellac or the like to the inner surface of the forehead of a doll's head in suitable relation to the eye-sockets.

It has been found difficult to properly support 25 glass eyes within the head of a doll in such manner as to permit the rolling action of the eyes in accordance with the movement of the doll, and difficulty has also been found in suitably connecting the 30 fragile glass eyes of a pair of eyes with a bridge or connecting rod, from which a weight is ordinarily suspended. My invention is in part designed to afford suitable means for connecting glass eyes in pairs and 35 also means for suspending the eyes of the pair or eye-set within the head of a doll in such manner that the eyes may have a rocking motion and also maintain their proper relation to the eye-sockets in the head of a 40 doll.

The invention and satisfactory means for carrying the same into effect will be fully understood from the detailed description hereinafter presented, reference being had 45 to the accompanying drawings, in which:

Figure 1 is a vertical section through the face of a doll and eye mechanism embodying the essential features of my invention, the section through the eye mechanism being 50 vertically through the bridge or rod connecting the eyes of a pair of eyes;

Fig. 2 is a rear elevation of an eye-set embodying my invention;

Fig. 3 is a front elevation of the same;

Fig. 4 is a central vertical section through 55 one of the eyes and its connected devices;

Fig. 5 is a top view, partly broken away, of the same;

Fig. 6 is a detached central section through a thimble I apply to the neck of the 60 eye as means for holding the eye and securing the same to the bridge-piece;

Fig. 7 is an inner end view of the same;

Fig. 8 is a sectional view of the same, taken at right angles to the section of Fig. 6; 65

Fig. 9 is a modified construction showing the two hangers for the eyes as connected together, and

Fig. 10 is a side elevation, partly broken away and partly in section, of one of the 70 eyes.

In the drawings, 15 indicates the face portion of the head of a doll, and 16, 17, respectively, denote the right eye and left eye for the doll. The eyes 16, 17 are of substantially corresponding construction and mounted on a bridge-piece 18 which connects the eyes to form a pair of eyes and supports a rod 19 on whose lower end is secured the customary weight 20. 80

The eye-set is suspended by hanger arms 21 which are substantially alike and secured upon a seat 22 formed at the inner surface of the forehead of the doll's face, said seat being inclined downwardly and inwardly 85 and the upper ends of the hanger arms or bars 21 being secured thereto by shellac or other cementitious material 23 applied to the upper ends of said arms, as shown. The upper ends of the arms 21 are preferably 90 formed with openings 24 through which the shellac 23 may pass and thereby aid in anchoring the arms 21 upon the seat 22. The seat 22 constitutes the only novel feature of the head of the doll, and this feature being 95 located at the middle of the inner surface of the forehead of the doll, is one of importance in enabling a workman to properly position the eye-set with relation to the usual eye-sockets to be found in dolls' heads. The 100 seat 22 compels the hanger bars 21 to take a downwardly and inwardly inclined position, and said hangers may be independently bent, when necessary, to adapt the eyes suspended by them to irregularities found in 105 and adjacent to the eye-sockets of a doll's head.

The eyes 16, 17 are alike, and each consists of a globular shell, preferably of glass, bearing at the front thereof a representation 110 of the iris of the eye, and at the rear side thereof a neck 25, which I utilize as an im-

portant feature in the mounting of the eyes on the bridge-piece 18. The eye-shell is hollow, as shown in Figs. 4 and 10, and is integrally formed with the neck 25, and said shell being of glass is smooth and has a bright polished surface and is of a more or less fragile nature. The fact that the eye-shell is hollow and of glass and has a polished surface necessitates the provision 10 of special means for connecting the same with the bridge-piece and for suspending the eyes against the eye-sockets of the doll's head, and in these respects my invention involves metallic thimbles 26 for engaging the necks 25 and special stirrups 27 formed at the lower ends of the hanger arms or bars 21 for engaging the globular portions of the eyes and suspending said eyes in a manner permitting them, without losing 20 their position, to have a rocking or rolling movement.

The thimbles 26 for a pair of eyes are alike in construction and each thimble 26 constitutes a hollow metallic cap having a closed outer end 28 and flaring sides 29 adapted to fit upon the outwardly tapering neck 25, and preferably each thimble 26 has slit spring fingers 30 which may be inserted within the neck 25, as shown in Fig. 4, and 30 aid in anchoring the thimble upon the neck of the eye, shellac or the like 31 being employed to fasten the thimble upon the neck 35. The shellac 31 may be placed within the neck 25 or within the thimble 26 as a preliminary step and the thimble then applied to the neck 25, the spring fingers 30 being pressed together at their outer ends and pushed into said neck and therein being allowed to spread. After the shellac 31 has 40 hardened it will be found that it will securely fasten the thimble upon the neck 25 in a manner preventing the rotation of said thimble on or the withdrawal of the same from the neck. The sides of the outer portions of the thimble 26 are formed with aligned apertures 32 to receive the end of the bridge-piece or rod 18, and the outer closed end 28 of the thimble 26 is formed with a threaded aperture 33 to receive a binding screw 34 adapted to engage the bridge-piece 18 and bind the eye in position on said bridge-piece. Each eye may be adjusted along the bridge-piece to suit the spacing of the eye-sockets of the doll's head, and 50 when adjusted the eyes may be rigidly secured to the bridge-piece by the tightening of the screws 34. The thimbles 26 afford reliable and convenient means, in coöperation with the necks 25 of the eyes, for securing the eyes upon the bridge-piece and permitting of the adjustment of the eyes on said bridge-piece, such adjustment of the eyes being the movement of the eyes either toward or from each other and the move-

ment of the eyes angularly on said bridge-piece, and said eyes being finally secured in their adjusted positions with relation to each other and to the head of the doll by means of the screws 34. 65

The rod 19 is rigidly secured to the bridge-piece 18 and the weight 20 is rigid with the lower end of said rod, and the purpose of the said rod and weight is, as usual, to effect a rolling or rocking movement of the eyes 16, 17 during the movement of the doll to a 75 reclining position or from said reclining position to an upright position.

The hanger-arms or bars 21 are preferably of sheet metal, and the novelty in said arms or bars resides in the formation at the lower 80 ends thereof of the stirrups 27 to receive the eyes 16, 17 and support the same against the eye-sockets of the doll's head. The metal of the arms or bars 21, at the lower ends thereof, is cut out to form large openings and 85 spread laterally to form flat band stirrups 27 which are less in diameter than the diameter of the eye-shells and afford smooth surfaces engaging the smooth globular surfaces of said shells. The stirrups 27 are deflected or 90 dished rearwardly so as to conform as nearly as may be to the globular formation of the eye-shells. The eyes are inserted into the stirrups 27 from the front thereof, the stems 25 and thimbles 26 passing through said 95 stirrups and the eyes being arrested from the fact that the stirrups are not sufficient in diameter to permit the eyes to pass entirely through them, the eyes becoming arrested in said stirrups when in about the 100 position shown in Fig. 1. The stirrups 27 loop around and engage the eyes at the rear of the vertical center line thereof, but to the front of the thimbles 26 so that said stirrups directly engage the smooth surfaces of the 105 eye-shells and afford a bearing for the same. The hanger arms 21, together with the stirrups 27, keep the eyes properly against the eye-sockets of the doll's head, and the surfaces of said stirrups engaging the eyes permit the eyes, without undue friction, to perform a rolling action under the influence of the weight 20 acting through the bridge-piece 18 on the thimbles 26 and necks 25. 110 The smooth surfaces of the eyes and the smooth inner surfaces of the stirrups 27 permit the eyes to have a rolling action without losing their relation to the stirrups or to the eye-sockets. The eyes are hung within the stirrups 27 and supported at their front portions in the eye-sockets of the doll's head. The manner of supporting the eyes by means of the stirrups 27 is important in carrying out the best form of my invention. It is to be noticed that the eye-shells are not cut or 115 otherwise treated to adapt them to the stirrups 27, and also that the necks 25 of the eye-shells are utilized to coöperate with the 120 125

thimbles 26 in receiving the bridge piece 18 by which the eyes of a pair of eyes are connected in a manner permitting them to be independently adjusted.

5 Fig. 9 illustrates a modification in that the two hanger arms, which I therein number 40, are connected together by a pivot 41. The arms 40 correspond with the aforesaid arms 21 and have at their lower ends stirrups 42 corresponding with the stirrups 27 of Figs. 1, 2 and 3.

What I claim as my invention and desire to secure by Letters Patent, is:

1. An eye-set for dolls and the like comprising a pair of globular eye-shells bearing at the front thereof a representation of the iris and having rearwardly extending integral necks, thimbles fitting over said necks and having spring fingers entering said necks, means securing the thimbles on said necks, a bridge connecting said thimbles, means for effecting a rolling action of the eyes on the movement of the doll and hangers secured within the head of the doll and having stirrups engaging the surfaces of the eye-shells and permitting of the movement of the same therein.

2. An eye-set for dolls and the like comprising a pair of globular eye-shells bearing a representation of the iris at the front thereof, means connecting said eye-shells to form a pair of eyes, means for effecting a rolling action of the eyes on the movement of the doll, and hangers having open stirrups encompassing the globular portion of the eye-shells and freely supporting the eyes within the head of the doll.

3. In combination, a doll's head having on the inner surface of the forehead thereof a downwardly and inwardly inclined seat, a pair of globular smooth surfaced eyes, hangers adapted to be secured to said seat and having open stirrups freely encompassing and affording bearings for said eyes, and means for effecting a rolling action of the eyes on the movement of the doll.

4. An eye set for dolls and the like comprising a pair of globular eye-shells, means for affecting a rolling action of the eyes on the movement of the doll, and open stirrups adapted to be secured within the head of the doll and freely receiving and encompassing the globular portion of said eyes and affording bearings for the same.

5. An eye-set for dolls and the like comprising a pair of globular eye-shells, means for effecting a rolling action of the eyes on the movement of the doll, and open stirrups adapted to be secured within the head of the doll and freely receiving and encompassing

the globular portion of said eyes and affording bearings for the same, said stirrups being rearwardly dished to receive and retain the eyes while permitting of their free rolling action.

6. An eye-set for dolls and the like comprising a pair of globular eye-shells bearing a representation of the iris at the front thereof, hangers having openings at their upper ends and adapted to be secured by shellac or the like to the inner forehead of the doll's head and having at their lower ends open stirrups encompassing the globular portions of the eyes at the rear of the center thereof and affording bearings in which the eyes may have free motion, and means for effecting a rolling action of the eyes on the movement of the doll.

7. An eye-set for dolls and the like comprising a pair of globular glass eye-shells bearing a representation of the iris at the front thereof, means connecting said eye shells at the rear thereof, means for effecting a rolling action of the eyes on the movement of the doll, and hangers having open stirrups supporting and encompassing said eye-shells at the globular portion thereof and affording free bearings within which said eye-shells may have a rocking action.

8. An eye-set for dolls and the like comprising a pair of globular glass eye-shells bearing a representation of the iris at the front thereof, means connecting said eye shells at the rear thereof, means for effecting a rolling action of the eyes on the movement of the doll, and hangers having open stirrups supporting and encompassing said eye-shells at the globular portion thereof and affording free bearings within which said eye-shells may have a rocking action, said stirrups being dished rearwardly to form broad bearing surfaces for the eye-shells.

9. An eye-set for dolls and the like comprising a pair of globular glass eye-shells bearing a representation of the iris at the front thereof and having rearwardly extending integral neck portions, means connecting the neck-portions of said eyes to form a pair of eyes, supporting means for the eyes comprising open stirrups freely receiving the globular portions of the eyes and forming bearings engaging the smooth surfaces thereof, and means for effecting the rolling action of the eyes in said bearings on the movement of the doll.

Signed at New York City, in the county of New York and State of New York, this 17th day of May, A. D. 1920.

SAMUEL MARCUS.
